(57) **CLAIM**

The ornamental design for a nozzle for a snap engagement dispensing assembly, as shown and described.

DESCRIPTION

FIG. 1 is a top front perspective view of a nozzle for a snap engagement dispensing assembly according to the present invention.

FIG. 2 is a front side view of the nozzle of FIG. 1.

FIG. 3 is a right side view of the nozzle of FIG. 1, the left side view being a mirror image thereof.

FIG. 4 is a rear side view of the nozzle of FIG. 1.

FIG. 5 is a cross-sectional side view of an interior side of one locking arm of the nozzle of FIG. 4, taken along line 5-5, and an identical section taken in the opposite direction showing the interior side of the other locking arm shown in FIG. 4 is a mirror image thereof.

FIG. 6 is a top end view of the nozzle of FIG. 1; and, FIG. 7 is a bottom end view of the nozzle of FIG. 1.

The broken lines in the figures are shown for the purpose of illustrating boundaries of the claimed design and the areas inside the broken line boundaries form no part of the claimed design.
